PLANOGRAPHIC PRINTING

Filed Feb. 2, 1931

UNITED STATES PATENT OFFICE

HOBART N. DURHAM, OF JACKSON HEIGHTS, NEW YORK

PLANOGRAPHIC PRINTING

Application filed February 2, 1931. Serial No. 512,983.

The present invention relates to planographic printing, and more particularly to a novel process of and apparatus for the preparation, moistening, and treatment of the metal plates generally used in planography.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawing, referred to herein and constituting a part hereof, illustrate one embodiment of the invention, and together with the description, serve to explain the principles of the invention.

The single figure of the drawing diagrammatically illustrates the present preferred embodiment of apparatus in accordance with the present invention and is typical of the apparatus by which the process of the present invention may be carried into effect.

The present invention provides a process and apparatus for the etching of metal plates for use in the planographic printing processes, and the invention has for a further object the provision of a process and apparatus for dampening the metal plates during the process of printing, and maintaining them in such a condition that they will be properly inked and will remain in their original condition throughout long runs.

In accordance with the present invention, which is particularly adapted for use in connection with the planographic printing of metal plates in which the metal of which the plate is formed is different from the metal or alloy of which the dampening roller is formed, means are provided for impressing an electric potential on the metal plate and the dampening roller to cause an electric current to be applied to the plate and the roller, for the purpose of neutralizing the electrolytic action induced by the differ-

ent potentials of the plate and roller when the plate and roller are electrically connected by the etching solution which is supplied to the surface of the metal plate by the dampening rollers or for the purpose of preparing the plate for printing or for increasing the life of the plate. In the preferred embodiment of the invention, the dampening rollers and the metal plate are electrically insulated from each other, in the sense that there is no metallic conduction between them through the frame of the press.

Other features of the invention will be initially pointed out in connection with the following detailed descriptions of the present preferred embodiment of the invention, and it will be understood that the foregoing general description and the following detailed description are both exemplary and explanatory but not restrictive of the invention.

In accordance with the process of the present invention, and during the normal operation of the printing press, an electric current is impressed on the planographic plate and the dampening rollers, the direction of flow of the current, the amount and voltage of the current being so regulated that the electro-motive force induced by the difference in the metals of which the plate and dampening rollers are made is completely neutralized, or is neutralized to such an extent that no appreciable electrolytic action takes place between the metal planographic plate and the rollers of the dampening mechanism, notwithstanding the fact that they are electrically connected by the electrically-conducting etching solution employed for dampening.

Further in accordance with the process of the present invention, the planographic plates may be etched, to condition them for inking, after being placed on the printing press, and for this purpose, the inking rollers of the press, are placed out of contact with the planographic plate, and the plate cylinder of the press is slowly revolved in the press, contacting with the dampening apparatus, and electrically connected with the metal dampening roller by the electrically-conducting etching solution, while a current is passed

from the dampening roller to the metal plate to etch the metal plate.

In case the dampening roller and metal planographic plate are formed of the same metal, as is sometimes the case, the current may be passed from the planographic plate to the dampening roller, to electrodeposit a thin film of relatively porous, water-receptive, ink-rejecting metal on the non-printing portions of the plate, which are not covered with the resist or have not taken ink during the "rolling up" of the plate.

If, during the operation of the press, and after a great many impressions have been taken from the plate, the plate is taking ink in those portions which are intended to be ink-rejecting, or if the impressions are too heavy, the current applied to the plate may be adjusted to such a value that the water-receptive portions of the plate are etched, thus tending to make the impressions less heavy and to render the non-printing portions of the plate more strongly ink-rejecting.

By using a dampening roller formed of the same metal as the planographic plate being printed, and by adjusting the voltage and current to such a value that metal is deposited on the water-receptive areas of the printing plate at an exceedingly slow rate, or by periodically raising the current and voltage to such a value that metal is removed from the dampening roller and is electro-deposited on the non-printing portions of the plate, the plates can be printed indefinitely, as the metal worn away during the printing process will be replaced by the electro-deposition process and will accurately conform to the shape of the original design on the plate.

Referring now in detail to the present preferred embodiment of the apparatus according to the present invention, and by which the processes of the present invention may be carried out, there is provided an impression cylinder 10, cooperating with a plate cylinder 11, carrying the metal planographic plate, all of which may be of conventional construction. The inking apparatus for inking the printing portions, or ink-receptive portions of the metal planographic plate may also be of conventional construction, and preferably comprises a plurality of inking rollers 12 movable toward and from the plate cylinder and normally contacting with the plate and rolling thereover as the plate cylinder rotates, the inking rollers receiving their ink from an ink fountain 13 by means of a periodically oscillating ductor roller 14.

The dampening mechanism, according to the present invention preferably consists of a pair of composition, or fabric-covered rollers 15 contacting with the surface of the planographic plate and rolling thereover as the plate cylinder rotates, the dampening rollers also contacting with a metal dampen-

ing roller 16 which receives the etching solution to be applied to the surface of the rollers 15 and then to the surface of the plate, from a fountain 18 by means of a ductor roller 19 which periodically oscillates between the fountain roller 20 and the dampening roller 16.

Means are also provided for controlling the current normally flowing between the dampening roller and the metal planographic plate for preventing electrolytic action between the plate and roller, in case they are made of different materials, or for etching the metal planographic plate or electrolytic action between the plate and the roller, in case they are made of different materials, or for etching the metal planographic plate or electrodepositing metal on the planographic plate in accordance with the process set forth above. As embodied, and for the purpose of enabling a neutralizing current to be set up between the metal plate and the dampening roller 16, the dampening roller is mounted on an insulated shaft 21, or is insulated from the shaft by which it is rotatably mounted.

Means are also provided for supplying a current of a predetermined, yet easily variable, voltage to the plate and dampening roller, for the purpose of neutralizing the normal current flowing between the roller and plate, or for the purpose of inducing the flow of current between the plate and roller. For this purpose there is provided a potentiometer 22, connected at each of its ends with a source of electricity (D. C.) of substantially constant voltage, such as a storage battery 23, capable of delivering current at about four volts. The potentiometer is preferably provided with two variably positionable contacts 24 and 25 which can be positioned along the resistance independently of each other, one of these contacts (25) being electrically connected with the metal planographic plate on the plate cylinder, the other with the metal surface of the dampening roller 16. By this means, the potential applied to the dampening roller may be minutely varied from about +4 to -4 volts, thereby permitting the current to be varied to meet any of the press operating needs. Under normal operation of the press, and for neutralizing the electrolytic action between the dampening roller and the metal planographic plate, due to the fact that these elements are metallically connected, and assuming that a brass dampening roller and an aluminium plate is employed, a current of about 1.6 volts will be needed across the roller and plate, the positive lead from the potentiometer being connected with the roller, in order to eliminate slow etching action which the roller would otherwise exert on the plate.

For the purpose of enabling the operator to determine the direction of flow and amount of the current flowing from the plate to the

roller, or for determining when the current between the plate and roller is exactly neutralized, a polarized galvanometer or ammeter 27 is preferably included in the circuit 5 from the potentiometer to the plate and roller, and this ammeter may be of any form which will show the direction of flow of the current.

The invention in its broader aspects is not limited to the specific mechanisms shown and 10 described but departures may be made therefrom within the scope of the accompanying claims without departing from the principles of the invention and without sacrificing its chief advantages.

15 What I claim is:—

1. The process of preparing planographic plates which includes increasing the water-receptive qualities of the non-printing portions of the plate by electrolytic action while 20 the plate is positioned on the press by which it is to be printed.

2. The process of preventing the electrolytic etching of planographic plates while being printed on a press employing a dampening roller of a metal different from that of the 25 plate which includes neutralizing the galvanic action induced by the dampening liquid between the plate and the dampening roller.

3. The process of treating planographic 30 plates which includes, placing the plate on the plate cylinder of the press on which it is to be printed, preliminarily etching the plate while on the press, thereafter preventing etching of the plate by galvanic action, and there- 35 after electrolytically treating the non-printing portions of the plate to maintain them water-receptive.

4. In a planographic press, a plate supported on a plate cylinder, dampening roller for 40 moistening the plate during the printing operation, said plate and dampening means having an electric current flowing between them and means for neutralizing the electrolytic action between the plate and the roller.

45 5. In a planographic press, a planographic plate, dampening means contacting with the plate for moistening the plate, said plate and dampening means having an electric current flowing between them and means for controlling the flow of current between the plate and the dampening means.

6. In a planographic press, a planographic plate, dampening means contacting with the plate for moistening the plate, said plate and dampening means having an electric current flowing between them and means for supplying current to the plate and dampening means to control the electrolytic action between them.

60 7. In a planographic press, a planographic plate, dampening means contacting with the plate for moistening the plate, a source of electric current connected with the plate and dampening means and means for varying the 65 voltage and direction of flow of the current.

8. In a planographic press, a planographic plate dampening, means contacting with the plate for moistening the plate, and a source of electric current of variable voltage connected with the plate and dampening means. 70

9. The process of maintaining the quality of impressions from planographic plates during long runs, which includes electrolytically replacing the metal worn from the plate by the printing operation during the process 75 of printing.

10. The process of maintaining the quality of impressions from metal planographic plates during long runs which includes de- 80 positing metal of the same kind as that of which the plate is formed on the plate during the printing operation at substantially the same rate it is worn away by the printing operation.

11. The process of planographic printing 85 with a press employing metal plates and dampening rollers which includes impressing an electromotive force on the plate and rollers, and regulating the electromotive force in accordance with the operating needs of the press. 90

12. In a planographic press, a planographic plate, dampening means contacting with the plate for moistening the plate and including a roller formed of the same metal 95 as the plate and means for depositing metal from the roller on the non-printing areas of the plate.

13. In a planographic press, a planographic plate, dampening means contacting with the plate for moistening the plate and including a metallic roller, and means for impressing an electromotive force on the plate and roller to etch the plate. 100

14. The process of maintaining the quality 105 of impressions from printing plates during long runs which includes electrolytically de- positing metal on the surface of the plate while the plate is mounted in printing position on the press. 110

15. The process of maintaining the quality of impressions from printing plates during long runs which includes electro-depositing metal on the plate surface during the printing 115 operation to replace metal worn therefrom by printing.

16. In a printing press, the combination of a printing plate, a metal roller adjacent to said plate and electrically connected with said plate by means of a liquid conductor, and 120 means for impressing an electric potential on said plate and roller to cause electrodeposition of metal on said plate.

In testimony whereof, I have signed my name to this specification.

HOBART N. DURHAM.
